UNITED STATES PATENT OFFICE.

NICOLAS A. BUHLE, OF NEW YORK, N. Y.

METHOD OF ENAMELING METAL FOR JEWELRY AND OTHER FANCY ARTICLES.

SPECIFICATION forming part of Letters Patent No. 299,054, dated May 20, 1884.

Application filed December 22, 1883. (Specimens.)

To all whom it may concern:

Be it known that I, NICOLAS A. BUHLE, of the city, county, and State of New York, have invented certain new and useful Improvements 5 in Methods of Enameling Metals for Jewelry and other Fancy Articles, of which the following is a specification.

This invention has reference to an improved method of enameling metals to be used for 10 dress and sleeve buttons, sign-letters, jewelry, and other fancy articles; and the invention consists in covering a suitable metallic foundation-plate with a layer of broken enamel of uniform thickness and then exposing the so- 15 covered plate to white heat, whereby the enamel liquefies and forms a uniform coating of enamel on the plate.

In the accompanying drawings, Figure 1 represents a front view, and Fig. 2 a vertical 20 transverse section on line yy , Fig. 1, of a metal plate enameled by my improved method.

Similar letters of reference indicate corresponding parts.

In carrying out my invention the surface of a 25 foundation-plate, A, of copper or other suitable metal, is first thoroughly cleaned with acids and then covered with a layer, B, of broken glass enamel, which layer is applied in uniform thickness over the entire surface of the 30 foundation-plate. The so-covered plate is

placed into a muffle and exposed to white heat in the same, by which the enamel liquefies, so that the individual particles or pieces of enamel run into each other and form a uniform coating of enamel over the entire surface of 35 the foundation-plate.

By mixing differently-colored enamels a great variety of colored effects can be obtained.

The enamel has the appearance of gayly-colored mottled ware, which can be used to advantage for various ornamental and fancy articles.

Having thus described my invention, I claim as new and desire to secure by Letters Patent— 45

The method herein described of enameling metal, which consists in covering a metallic foundation-plate with a layer of broken enamel of uniform thickness and then exposing the so-covered plate to white heat, where- 50 by the enamel liquefies and forms a uniform coating on the metal plate, substantially as set forth.

In testimony that I claim the foregoing as my invention I have signed my name in presence of two subscribing witnesses.

NICOLAS A. BUHLE.
